UNITED STATES PATENT OFFICE.

GROSVENOR N. ALLEN, OF ONEIDA, NEW YORK, ASSIGNOR TO ONEIDA COMMUNITY, LIMITED, OF ONEIDA, NEW YORK, A CORPORATION OF NEW YORK.

DESIGN FOR A HANDLE FOR SPOONS, FORKS, OR SIMILAR ARTICLES.

45,976.

Specification for Design.

Patented June 23, 1914.

Application filed March 30, 1914. Serial No. 828,404. Term of patent 14 years.

To all whom it may concern:

Be it known that I, GROSVENOR N. ALLEN, a citizen of the United States, residing in the city of Oneida, county of Madison, State of New York, have invented a new, original, and ornamental Design for Handles for Spoons, Forks, or Similar Articles, of which the following is a specification, reference being had to the accompanying drawing, which forms part of the same, and in which—

Figure 1 is a top view of a handle of a spoon or fork showing my new design; and Fig. 2 is a corresponding sectional view

somewhat in perspective showing that each of the panels forming the front of the handle is substantially flat or straight as they appear in a cross-section taken transversely through the handle.

What I claim is:

The ornamental design for a handle for spoons, forks or similar articles, substantially as shown and described.

GROSVENOR N. ALLEN.
